TOWEL BAR

Walter L. Spangler, Kokomo, Ind., assignor to
B-W Manufacturers, Inc., Kokomo, Ind., a corporation of Indiana

Application February 28, 1950, Serial No. 146,818

5 Claims. (Cl. 211—86)

1

It is an object of this invention to produce a towel bar or rack adapted for attachment to a face of a door and capable of supporting towels, light articles of clothing, etc. Another object of the invention is to provide a towel bar which can be removably applied to a door without damaging the latter, which will not interfere with ordinary opening and closing of the door, and which will be applicable readily to doors of different widths. A further object of the invention is to produce a light-weight towel bar which can be simply and economically manufactured and which will possess an attractive appearance.

In carrying out the invention, I employ a pair of brackets, conveniently formed of sheet metal, adapted loosely to embrace opposite edges of a door. Each of such brackets embodies a support having an end portion spaced from the door and directed inwardly thereof. The end portions of the supports are screw-threaded and adapted to be received in the ends of a helical tension spring. With the brackets in place embracing opposite edges of the door, the spring will be stressed and will exert on each bracket an inwardly directed effort sufficient to hold the bracket in position. Extensibility of the spring permits application of the device to doors of varying widths.

The accompanying drawing illustrates the invention: Fig. 1 is a perspective view illustrating a towel bar in position on a door; Fig. 2 is an elevational view illustrating one end of the towel bar; Fig. 3 is a horizontal section on the line 3—3 of Fig. 2; Fig. 4 is a fragmental detail view similar to Fig. 2 but showing the spring broken away; and Fig. 5 is a section on the line 5—5 of Fig. 4.

Referring to Fig. 1, it will be apparent that the device consists essentially of a pair of brackets 10, adapted to embrace opposite side edges of a door 11, and a tension spring 12, which extends horizontally between such brackets, draws them toward each other, and seats them against the sides of the door.

Each bracket 10 is conveniently formed of a sheet-metal strip bent to provide a front 15 adapted to lie against one face of the door, a flange 16 adapted to lie against one side of the door, and one or more ears 17 adapted to engage the opposite face of the door. The front 15 and the ears 17 are parallel to each other and are spaced apart by a distance substantially equal to the thickness of the standard interior door. To stiffen the front 15, it may be formed with a pair of spaced stiffening beads or ribs 18.

Secured to each bracket 10 is a support 20

5 to which the adjacent end of the spring 12 is attached. Conveniently, the attachment of the support 20 to the bracket 10 is effected in the manner illustrated in Fig. 3, a portion 21 of the front 15 defined by two spaced vertical strips being offset forwardly to provide a socket and the support 20 being formed of strip stock bent into a U-shape and having one leg 22 received in the socket 21. To anchor the support in place, 10 the assembly may be subjected to a press operation which forms a transverse groove 26 in the leg 22 and forces part of the metal of the socket 21 into such groove, as indicated at 23. Conveniently, the support 20 is formed of semi-circular stock and is bent with its flat face on the outside of the bend, so that such flat face, seated against the outer surface of the bracket-front 15 beyond the limits of the socket 21, will prevent the support from rotating in the socket. 15 The end of the other leg 24 of the support 20 may be adapted for attachment to the spring 12 by forming in its opposite edges series of oppositely oblique grooves 25 constituting in effect a male thread adapted to be threadedly received 20 in the adjacent end of the spring 12. Desirably, such grooves are formed by a pressing operation 25 in which the extreme end of the leg 24 is tapered to a width such that it can enter the spring 12. The width of the stock from which the support 20 is formed is greater than the internal diameter of the spring 12, as will be clearly evident from Fig. 4; and as the spring-end is screwed on the end of the leg 24 with the aid of the grooves 25, the turns of the spring will be forcibly 30 expanded and caused to grip the end of the leg 24 tightly. A characteristic of this type of connection is that the torque applied to the spring body in screwing it on the leg-end is in the direction which tends to unwind the spring, expand its turns, and reduce the force with which they grip the leg-end. If an attempt is made 35 to remove the spring by applying reverse torque to its body, such reverse torque tends to contract the spring to cause its end turns to grip the leg-end securely and oppose such unwinding.

The bracket and support construction described lends itself to formation of aluminum, and hence the brackets and supports may be made relatively light in weight. The spring 12 is made 40 of a length such that it will be subjected to substantial tension when applied to even relatively narrow doors; and as a result of the tension in the spring, it will not undergo objectionable vertical displacement under any loads to which 45 it will be ordinarily subjected in use. Clearance

between the sides of a door and sides of its associated frame is ordinarily more than sufficient to permit reception of the flanges 16 without interfering with opening and closing of the door.

I claim as my invention:

1. In a device of the type described, a pair of brackets adapted to embrace the opposite vertical sides of a door, each of said brackets being formed of sheet-metal and including a front adapted to lie against the face of the door, a portion of said bracket-front intermediate the height thereof being offset forwardly to provide an open-ended horizontally extending socket, a separate U-shaped support formed of strip stock associated with each bracket and having horizontal legs one of which is received and secured in the socket, and a helical tension spring, the other leg of each support being provided with a conical, male screw thread and being screw-threadedly received in the adjacent end of said spring.

2. In a device of the type described, a pair of brackets adapted to embrace the opposite vertical sides of a door, each of said brackets being formed of sheet-metal and including a front adapted to lie against the face of the door, a portion of said bracket-front intermediate the height thereof being offset forwardly to provide an open-ended horizontally extending socket, a separate U-shaped support associated with each bracket and having horizontal legs one of which is received and secured in the socket, the support-leg received in said socket having a flat side which engages the front of the bracket beyond at least one end of the socket, and a helical tension spring, the other leg of each support being provided with screw threads co-operating with the turns of the spring to secure the support and spring together.

3. In a device of the type described, a pair of brackets adapted to embrace the opposite ver-

tical sides of a door, each of said brackets being formed of sheet-metal and including a front adapted to lie against the face of the door, a portion of said bracket-front spaced outwardly from

5 the inner end thereof being offset forwardly to provide an open-ended horizontally extending socket, a separate U-shaped support associated with each bracket and having horizontal legs one of which is received and secured in the socket and projects inwardly therebeyond over and in contact with the bracket-front, and a helical tension spring having its ends secured respectively to the other legs of the two supports.

4. The invention set forth in claim 3 with the addition that each support is formed of bent stock of substantially semicircular cross-section the flat face of which engages the bracket-front and prevents rotation of the support in the bracket.

5. The invention set forth in claim 4 with the addition that the ends of said other support legs are tapered and provided at their edges only with screw-threads screw-threadedly engaging end turns of said spring.
